UNITED STATES PATENT OFFICE.

JONAS NORTHROP, OF HOPEDALE, MASSACHUSETTS, ASSIGNOR TO WILLIAM F. DRAPER, OF HOPEDALE, MASSACHUSETTS.

FILLING-REPLENISHING LOOM.

No. 926,354.

Specification of Letters Patent. Patented June 29, 1909.

Application filed March 23, 1909. Serial No. 485,243.

To all whom it may concern:

Be it known that I, JONAS NORTHROP, a citizen of the United States, residing at Hopedale, in the county of Worcester and State of Massachusetts, have invented an Improvement in Filling-Replenishing Looms, of which the following description, in connection with the accompanying drawings, is a specification, like characters on the drawings representing like parts.

The invention to be hereinafter described relates to filling replenishing looms and more particularly to that type wherein the filling carrier in a shuttle is replaced by another filling carrier at desired times. In such looms, wherein the filling carrier in the shuttle is replaced by another filling carrier having a supply of filling thereon, it is desirable that the shuttle assume such control of the new filling as to insure proper delivery of the same during the picking operations in order to prevent breakage, as well understood by those skilled in the art; and, with this fact in view, the aims and objects of the present invention will best be made clear by the following description and accompanying drawings of one form of means for carrying the invention into practical effect, it being understood that said invention is not circumscribed by the details of said means, the true scope thereof being defined by the claims.

In the drawings: Figure 1 is a plan view of a sufficient portion of the loom structure to illustrate the invention and its relation to adjacent parts, the lay being shown in front position and the shuttle as having just been supplied with a filling carrier; Fig. 2 is a view similar to that of Fig. 1, showing the lay as having moved a short distance on its back stroke and just prior to the pick, some of the parts being broken away or omitted to clearly show those beyond; Fig. 3 is a like view showing the lay as having moved further back and the shuttle as being "picked", some of the parts being omitted; Fig. 4 is a side view of the right hand end of Fig. 1, showing more particularly the relation of the shuttle, filling end, and parts of the present invention at about the time of filling change; and Fig. 5 is an end view, looking in the direction of the arrow, Fig. 4.

The loom frame including the breast-beam A, the lay B, its actuating means, the shuttle box C, the picker stick D and picker

E for moving the shuttle through the shed, the means for presenting a filling carrier to transferring position, shown partly in full and dotted lines, Fig. 1, and supported, as by the bracket 1, the transferer F, and its associated parts by which a filling carrier may be transferred to the shuttle, may be of any usual or desired character and construction, and being well understood by those skilled in the art, need no further description. It is likewise usual in this type of loom to lead the filling ends from the several carriers, which are to be transferred to the shuttle, as occasion demands, to a point at the loom side, as for instance to a point 2, Figs. 1, 2 and 3, in prolongation of the axis 3 of the filling carrier feeder, said feeder in the present illustration being of the well known rotary type. When such form of filling feeder is employed and the ends of the filling 4 are held at the point stated, it is usual to provide a wheel or guide G, Fig. 1, preferably of a diameter sufficient to deflect the filling ends toward the top of the shuttle box, so that the shuttle S of the self-threading type may assume control of the filling or become threaded as it leaves the shuttle box. In practice, however, it frequently happens that the shuttle fails to assume control of the filling on the first pick owing to various causes, among which may be mentioned that the filling fails to drop into proper threading position on the top of the shuttle before the shuttle moves either backward with the lay or on its pick, and as the lay moves back, the filling, between the carrier and end, becomes deflected partly cross-wise over the end of the shuttle and the shuttle fails to thread. The effect is that on the next pick the filling is broken.

The present invention may be employed either with the character of filling replenishing mechanism shown, wherein a feeder and filling end holder form parts, or it may be employed with any general character of means operative at desired times to effect replenishment of the filling in a shuttle, and with this understanding, one form or embodiment of the invention will now be described.

Mounted on the lay B is a member 5, which, for identification, may hereinafter be termed the filling director. This filling director preferably comprises a plate secured to the lay by suitable means, as, for

instance, the screw bolt and nut 6, 7, the end of the said plate being downturned, as shown, and having a broadened or extended bearing to assist in maintaining it in fixed or adjusted position. The filling end director is shown as secured to the front portion of the lay and is provided with a part extending over the top of the shuttle box, C, said part reaching toward but stopping short of the rear wall of the shuttle box and preferably having a curved edge 9. The curved edge 9 preferably extends from a point 10, somewhat to the rear of the longitudinal axis of the shuttle S when said shuttle is in the shuttle box and positioned for replenishment, to a point near the outer or end portion of the shuttle box, substantially as shown, the construction being such that when the lay is in its forward position and a filling carrier has been transferred to the shuttle, the filling end 4 will extend from the carrier 11, Fig. 1, to the holding point 2, and around the guide G, somewhat in front of the part 10 of the filling end director, and as the lay moves back prior to the pick, for instance, as indicated in Fig. 2, the filling 4 between the carrier and point 2 will be engaged by and extend under the director, the curved edge 9 and general character of the director maintaining the filling in alignment with the axial center of the shuttle or thread passage 12 of the shuttle threading block. As the lay continues rearwardly and the shuttle starts on its first pick, as indicated by Fig. 3, the lead of the filling from the holding point 2 to the filling carrier 11 in the shuttle S will be controlled by the edge 9 of the director to maintain such axial alignment of the filling with the shuttle or thread passage and thereby insure that the shuttle will assume deliverable control of the filling on the first pick.

As indicated in Figs. 4 and 5, the part 4 of the filling between the carrier in the shuttle and the guide or wheel G not only extends somewhat backward but also upward, and the upward extension of the plate 5 of the director is such that the point 10 will engage above the filling as the lay moves back prior to the picking movement of the shuttle, and thereafter, as the shuttle is picked and the direction of the part 4 of the filling becomes more and more nearly perpendicular to the lay, the curve of the edge 9 will maintain the desired axial alignment of the shuttle or thread passage and filling.

It will be obvious to those skilled in the art that the action of the filling director serves to maintain a proper position of the filling between the carrier in the shuttle and the point of attachment of the filling end, so that the threading action of the shuttle on or prior to the first picking movement is rendered more certain and consequent breakage of filling is reduced. It will

also be obvious that the filling ends may be secured or held at other points than that indicated by the present embodiment of the invention, and that if held at a proper position with respect to the lay and shuttle box, the guide or wheel G would be unnecessary. 70

When the replenishing mechanism has transferred a fresh supply of filling to the shuttle and the latter has assumed control of the filling or become threaded, there will still be an end of filling extending from the selvage of the cloth to the point 2 where it is made fast. It is desirable that this end be not permitted to get into the shuttle-box, otherwise it is liable to be taken into the shed by the shuttle on one of its picks, thereby producing a bad place in the cloth. The present invention obviates this defective action by the downwardly deflecting portion of the director extending in front of the shuttle box which, as the lay goes back, deflects the engaged filling ends outside and to the front of the shuttle-box. This deflecting portion of the director and its action will best be understood from Fig. 5, wherein 3' indicates the downwardly directing portion extending to the front of the shuttle-box, and the dotted lines X indicate the position the filling end assumes as the lay moves back, it being finally disposed and deflected 95 to the front of the shuttle-box where all danger of being engaged by the shuttle and carried into the shed is avoided.

Many changes in form, shape and disposition of the filling director will occur to those skilled in the art, and instead of being made of a plate it might be otherwise produced, and the present invention is intended to be generic in these respects, it being the first to provide a filling director immovably mounted with relation to the lay and operating to maintain axial alignment of the filling and shuttle or threading passage as the lay moves back. 100

What is claimed is:

1. In a filling replenishing loom, a lay, a shuttle box thereon, and a filling director fixed with relation to the lay and having a part extending over the top of the shuttle box from the front toward the rear thereof. 115
2. In a filling replenishing loom, a lay, a shuttle box thereon, and a filling director disposed in fixed position at the front of the shuttle box and having a portion extending part way over the top of the shuttle box 120 toward the rear thereof.
3. In a filling replenishing loom, the combination of a lay, a shuttle box mounted thereon, and a filling director fixed with relation to the lay and having a part provided with a curved edge extending over the top of the shuttle box part way to the rear thereof. 125
4. In a filling replenishing loom, the combination of a lay, a shuttle box, a filling director disposed at the front of the shuttle 130

box and having a curved filling engaging portion extending from the front part-way to the rear of the shuttle box above the threading block of a shuttle when in the shuttle box.

5. In a filling replenishing loom, the combination of a lay, a shuttle box thereon, a filling director movable with the lay and having a part fixed with relation to the lay and extending over the top of the shuttle box toward the rear thereof, and a curved portion extending from said part toward the end and front of the shuttle box.

10. In a filling replenishing loom, the combination of a lay, a shuttle box thereon, and a filling director comprising a part immovable with relation to the lay and extending from the front upwardly and toward the rear of the shuttle box to engage and position the filling.

15. In a filling replenishing loom, the combination of a lay, a shuttle box thereon, a filling director comprising a plate fixed with relation to the lay and having an edge portion extending diagonally from front toward the rear over the top of the shuttle box.

20. In a filling replenishing loom, the combination of a lay, a shuttle box thereon, and a filling director comprising a part fixed with relation to the lay and having a curved edge portion extending over the top of the shuttle box from a point near the outer end thereof to a point above the threading block

when the shuttle is in filling changing position.

35. 9. In a filling replenishing loom, the combination of a lay, a shuttle box, and a filling director comprising a plate fixedly mounted on the lay and having a portion extending from the front wall over the top of the shuttle box, said portion having an edge extending diagonally over the top of the shuttle box.

40. 10. In a filling replenishing loom, a lay, a shuttle box theron, a filling director fixed with relation to the lay and having a part 45 extending over the top of the shuttle box from the front toward the rear thereof, and a deflecting portion to deflect the filling end to the front of the shuttle box.

45. 11. In a filling replenishing loom, a lay, a shuttle box thereon, a filling director fixed with relation to the lay and having a part extending over the top of the shuttle box from the front toward the rear thereof, and 50 a deflecting portion downturned over the front of the shuttle box to deflect the filling end to the front of and below the top of the shuttle box.

55. In testimony whereof, I have signed my name to this specification, in the presence of two subscribing witnesses.

JONAS NORTHRUP.
